UNITED STATES PATENT OFFICE

PERCY E. HUNTER, OF PITTSBURGH, PENNSYLVANIA

PIPE-THREAD PROTECTOR

Application filed August 16, 1928. Serial No. 299,893.

My invention relates to thread protectors, such as are employed in protecting the threads of pipes, shafts, rods, etc. for the purpose of preventing injury thereto while being shipped or handled previous to installation.

Since thread protectors are commonly employed but once, being usually discarded entirely or used as scrap when removed from the pipes or rods, it is desirable to make them as cheaply as possible with due regard, however, to their effectiveness as protectors.

One object of my invention is to provide a protector that may be more easily applied than some of the forms now employed, and with less danger of damage to the threads.

Another object of my invention is to provide a protector that will not be likely to cause damage to the threads through handling of the pipe to which the protector is applied.

Another object of my invention is to provide means for more effectively retaining a protector in place.

Still another object of my invention is to simplify and improve generally the structure of devices of the character referred to and the method of applying the same.

Some of the various forms which my invention may take are shown in the accompanying drawing wherein

Fig. 1 is a longitudinal sectional view of a portion of a pipe equipped with one form of protector embodying my invention.

Fig. 2 is a view taken on the line II—II of Fig. 1.

Fig. 3 is a view similar to Fig. 1, but showing a modified form of protector.

Fig. 4 is a view taken on the line IV—IV of Fig. 2.

Fig. 5 is a view showing still another form of protector device.

Fig. 6 is a view taken on the line VI—VI of Fig. 5.

Fig. 7 is a perspective view of a key or stop member which may be employed in the structures of Figs. 3 to 6.

Fig. 8 shows another modification, and

Fig. 9 shows still another modification, for use with an internally-threaded pipe.

While, as above indicated, the invention is susceptible of use in various ways, for convenience of description, I will hereinafter describe it as employed in the protection of pipes.

Referring to Figs. 1 and 2; 10 represents a portion of a pipe whose threaded end is to be protected and 11 designates the protector. These protectors may be stamped from sheet metal or otherwise formed.

The protector is flared or of bell shape at its inner end, as indicated by the numeral 12. A series of pairs of cuts 13 are formed in the inner edge of the protector, by sawing or by means of dies, so that tongues 14 are formed which may be bent inwardly to the position shown in Fig. 1, after the protector is in place upon the pipe. This bending may be effected by a hammer or other tool and the tongues serve as stop lugs to prevent the protector from sliding off the pipe. In cases where it is desired to more effectively protect the threads against injury, I first place upon the threaded pipe end a liner 15 of soft material, such as card board, etc., and then slide the protector 11 into position over the liner and bend down the tongues 14. The lining is of such thickness that it will be pressed somewhat against the threads, thus offering frictional resistance to its withdrawal and its inner edge will either abut against or lie beneath the struck down tongues, so that it will serve as a stop or key member for the tongues.

The outer edge of the protector 11 is bent in as shown at 16, to form an annular seat for the extreme end of the pipe, holding it in a central position on the pipe, and thus more effectively protecting the threads and the pipe end against injury. The portion 16 may extend diametrically entirely across the pipe end, to prevent the entry of foreign matter into the pipe, or in other words, may be disk-shaped.

As above indicated, the tongues 14 may either engage the innermost thread turn to form stop lugs against withdrawal of the protector, or they may bear directly upon the peripheral surface of the lining.

By bending the tongues inward after plac-

ing of the protector, I avoid the necessity of screwing the protector into place upon the pipe end, and further reduce danger of injury to the thread during the placing of the 5 protector. When it is desired to remove the protector, a tool may be inserted beneath the tongues to bend them outwardly, or the protector may be unscrewed, the inner ends of the tongues moving along the thread grooves 10 as do the threads of ordinary collars.

In Figs. 3 and 4, I show a protector 17 formed somewhat after the manner of the 15 protector 11, but instead of forming tongues by slitting or cutting the inner flared end of the protector longitudinally, I form tongues 18 by making one cut or slit 19 in a direction longitudinally of the protector and another cut 20 in a direction circumferentially thereof, that is, at right angles to the longitudinal 25 slit 19. Adjacent to each of these cuts 19—20, I stamp depressions 21 upon the inner surface of the protector.

In applying the protector 17 to the pipe, I first place on the pipe one or more keys 25 or stop members 22, which have threads 23 that interfit with the threads of the pipe 10. These keys are so positioned on the pipe that they will lie within the pockets or recesses 21 of the protector 17. The tongues 18 are 30 then bent inward and serve as stop lugs which engage the key blocks 21, thus holding the protector against sliding movement off the pipe end, the inner walls of the pockets 21 serving to hold the keys in close fitting relation with the pipe threads.

When it is desired to remove the protector, it may be simply unscrewed from the pipe, the key blocks following the pipe thread during such unscrewing movement, or the 40 tongues 18 may be bent outwardly to their original positions, thus freeing them from the key or keys and permitting withdrawal of the protector. The pockets 21 are struck up from the smaller diametral portion of the 45 protector rather than from the flared portion thereof, so as not to increase the overall circumference of the protector, or cause protuberances on the protector that would interfere with rolling of the pipe during handling.

The key blocks 22 may be formed in any suitable manner, as for instance, by a stamping or casting operation, or by threading an annular metal ring and thereafter cutting it into sections.

Referring now to Figs. 5 and 6, I show a 55 protector 25 which resembles somewhat the protector 17, in that circumferentially-extending tongues 26 are formed by cutting the flared end of the pipe for short distances longitudinally and circumferentially thereof. However, instead of stamping pockets 27 60 from the body, or smaller diametral portion of the protector, I extend such pockets to approximately the extreme inner flared end of the protector. In Figs. 5 and 6, only two

holding tongues are shown instead of four tongues, as in the other figures. It will, of course, be apparent, that the number of holding tongues and keys may be varied to suit conditions. Blocks 22 may be employed in the structure of Figs. 5 and 6, as explained in discussion of Figs. 3 and 4.

In Fig. 8, I show still another form of device wherein a protector 28 has tongues 29 formed thereon somewhat after the manner of the tongues 14 of Figs. 1 and 2. However, instead of having such tongues bear directly upon the pipe or a lining, I bend them down over stop members 30, one of which may be provided for each tongue, or which stop members may be integrally formed and extend entirely around the pipe. It will be seen that when the protector 28 tends to slide off the pipe end, the stop members 30 will bind, by a wedge-like action, beneath the inclined under surface of the tongues 29. When it is desired to remove the protector 28 it is necessary only to bend the tongues 29 upwardly.

Referring to Fig. 9, I show a protector 31 for protecting an internally-threaded pipe. In this arrangement, a tongue 32 is bent into engagement with a stop member 33 that will function after the manner of the stop member 30 of Fig. 8, to prevent accidental withdrawal of the protector, the outer end of the protector being flanged or bent back, for holding the protector snugly in position and for protecting the pipe end.

I claim as my invention:—

1. A thread protector comprising a collar formed to fit over the threaded portion of a pipe, and being slit to provide a tongue upon its inner end that is capable of being bent inwardly, and a key member adapted to have locking engagement with the pipe thread and to be positioned in abutting engagement with the bent-in tongue.

2. A thread protector comprising a collar formed to fit over the threaded portion of a pipe, and being slit to provide a tongue upon its inner end that is capable of being bent inwardly, and a key member adapted to have locking engagement with the wall of the pipe and to be positioned for engagement by the bent-in tongue.

3. A thread protector comprising a collar formed to fit over the threaded portion of a pipe, the inner end of said collar being of flared or enlarged diameter, to provide an internal recess, a key member disposed within said recess and adapted to abut the wall of the pipe, and a tongue member carried by the collar and capable of being bent to partially embrace said key member.

4. A thread protector comprising a collar formed to fit over the threaded portion of a pipe, and having an internal recess, a key member disposed in said recess and adapted to seat against the wall of the pipe, and a member carried by the protector and mov-

able into abutting engagement with the inner end of the key.

5. A thread protector comprising a collar formed to fit over the threaded portion of a pipe, and having an internal recess at its inner end, a threaded key member disposed in said recess and adapted to seat against the pipe threads, and a member carried by the protector in abutting engagement with the inner end of the key member.

10. A thread protector comprising a collar formed to fit over the threaded portion of a pipe, and a key member engaging the pipe at a point inside the collar, the collar having a 15 weakened portion capable of being bent inwardly to form a lug for engaging the said key member.

15. The method of protecting threaded members which comprises placing a threaded 20 key in operative relation to the threads of said member, sliding a protecting sleeve into position overlying the said key and threads, and deflecting a portion of said sleeve into abutting engagement with a radial surface 25 of the key, to prevent accidental withdrawal of the sleeve.

20. A thread protector comprising a collar formed to fit over the threaded portion of a pipe and having an internal recess at its inner 25 end with walls extending radially, and a preformed threaded key member disposed within said recess in position to seat against the pipe threads, the radially-extending walls of the recess being of such depth as to 30 confine the key against movement in axial and radial directions relative to the collar.

35. A thread protector comprising a collar formed to fit over the threaded portion of a pipe and having an internal recess at its inner 40 end, the said end being flared, and a preformed threaded key member disposed within said recess in position to seat against the pipe threads, the radially-extending walls of the recess being of such depth as to 45 confine the key against movement in axial and radial directions relative to the collar.

In testimony whereof I, the said PERCY E. HUNTER, have hereunto set my hand.

PERCY E. HUNTER.
